PLUG ELECTRIC SWITCH

Milton Zuckerman, New York, N. Y., assignor to
Irving Haas, New York, N. Y.

Application November 26, 1935, Serial No. 51,666

2 Claims. (Cl. 173—328)

This invention relates to electric switches and particularly to an improved plug electric switch, and has for an object to provide a structure which may be quickly applied and removed and when applied may be locked in position.

Another object of the invention is to provide a plug for electric sad irons and for other devices using cylindrical terminals, the structure being such that the plug may be applied from either of two directions and then locked in place.

A further object, more specifically, is to provide a plug switch structure for round terminals wherein the contacts engaging the terminals are moved toward and from the terminal so that at one time they will grip the terminals and at another time they will release the terminals.

In the accompanying drawing:

Fig. 1 is a plan view of a plug switch disclosing an embodiment of the invention;

Fig. 2 is a longitudinal sectional view through Fig. 3 approximately on the line 2—2;

Fig. 3 is a sectional view through Fig. 1 approximately on the line 3—3;

Fig. 4 is a transverse sectional view on an enlarged scale through Fig. 1 approximately on the line 4—4; and

Fig. 5 is an enlarged view similar to the left hand end of Fig. 2 but showing the plug applied from the end.

Referring to the accompanying drawing by numeral, 1 indicates the plug as a whole and 2 and 3 terminals associated therewith. The terminals 2 and 3 may be the terminals used on an ordinary electric sad iron or any other device using electricity. Preferably the terminals 2 and 3 are provided with grooves 4 and 5, though this is not essential to a good contact. These grooves are provided so that the plug 1 may be locked to the terminals 2 and 3. The plug 1 is provided with a casing having a body 6 and a cover 7 which may be held in place in any desired manner, as for instance by the bolt 8. This casing is made from insulating material and encloses the respective gripping terminals 9 and 10. As these terminals are identical the same description will apply to both.

As shown in Fig. 2, terminal 9 is formed from a piece of wire or other metal having a loop 11 for accommodating the bolt 12 which connects the wire 13 to the terminal or contact 9. From the loop 11 the wire is formed into bars 14 and 15 which diverge to points 16 and 17. From points 16 and 17 to the points 18 and 19 the bars converge and then merge into a rounded socket structure 20. The wire is bent upwardly

at right angles at the outer end of the socket structure 20 and is then bent into a second socket structure 21. The socket structure 20 is adapted to grip the posts or terminals 2 and 3 when the plug is applied as shown in Fig. 4, while the socket 21 grips the terminals when the plug is applied from the end as shown in Fig. 5.

When the parts are in the position shown in Fig. 2, the plug may be slipped over the terminals 2 and 3 readily and then the thumb or hand member 22 is moved to the right from the position shown in Fig. 3. This thumb or hand member is connected by a bolt 23 to a cam bar 24. Guide pins 25 and 26 are carried by the cam bar and extend into the respective slots 27 and 28. For each of the terminals or contacts the cam bar 24 is provided with cam surfaces 29 and 30, whereby as the bar 24 is moved to the right as shown in Fig. 3 the cam surfaces just mentioned will act on the inclined parts of the terminal and cause the socket 20 to squeeze the terminal posts 2 and 3. This squeezing action takes place in the respective grooves 4. In this way a good electrical contact is secured and also the plug 1 is locked to the terminal posts 2 and 3. When the plug 1 is applied from the end as shown in Fig. 5, the same action takes place, except that the sockets 21 engage the posts 2 and 3 in the respective grooves 5. By reason of the construction just described the plug may be easily applied and easily removed, but when applied presents a locked construction and a good contact between the respective terminals.

I claim:

1. A plug electric switch including a plug formed with a casing having a pair of openings in one side and a pair of openings in one end, said openings being adapted to receive plug terminals at different times, a pair of terminals arranged in said casing, each of said terminals being formed with a pair of resilient bars merging into an inner structure presenting a pair of socket formations, said inner structure including a pair of bars inclined toward each other and at their point of nearest approach merging into a pair of facing arc-shaped socket ends, one socket formation normally positioned on each side of the aperture in the side of the casing and the other socket formation on each side of the aperture in the end of the casing, and a cam for each terminal positioned to straddle said inclined bars so that when moved in one direction it will move the socket structure into plug engagement position and lock the same in that position.

2. A plug for an electric switch comprising a hollow rectangular casing having a pair of openings in one side near one end for the reception of a pair of plug terminals, and a pair of openings in one end spaced the same distance apart as the first mentioned openings, a pair of terminals arranged in said casing, the terminals being arranged with one end adjacent the respective openings in the casing, each of said terminals comprising a pair of bars extending longitudinally of the casing having a tapering structure merging into arc-shaped ends having arc-

shaped offsets forming a pair of sockets, one socket being opposite the opening in the side of the casing while the other socket being opposite the opening in the end of the casing, a reciprocating cam bar carried by the casing and formed with two pairs of cam faces, each pair of cam faces acting on a terminal for moving said sockets to operative positions and a hand-operated member extending through said casing for reciprocating said cams. 5

MILTON ZUCKERMAN. 10
